UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

SEMAUTO PAPER WINDER.

Application filed April 27, 1921. Serial No. 464,834.

To all whom it may concern:

Be it known that FREDERICK COATES, a citizen of the United States, residing at Cincinnati, in the county of Hamilton and State of 5 Ohio, has invented certain new and useful Improvements in Semiauto Paper Winders, of which the following is a specification.

This invention relates to the manufacture of paper containers of the type commonly 10 known as paper cans.

More particularly the invention relates to a semi-automatic paper can body machine.

One important object of the invention is to improve and simplify the general 15 construction of devices of this character.

A second important object of the invention is to provide a machine of this description having improved pneumatic means for holding the strip of paper while the same is being 20 rolled.

A third important object of the invention is to provide, in a machine of this character, means for positioning the end of the paper strip and for pressing the two ends together 25 after the can body has been formed.

A fourth important object is to provide a machine of this character having improved means for successively breaking the vacuum and ejecting the can body after formation.

30 With the above and other objects in view, the invention consists in general of certain novel details of construction and combinations of parts hereinafter fully described, illustrated in the accompanying drawings, 35 and specifically claimed.

In the accompanying drawings, like characters of reference indicate like parts in the several views, and:—

Figure 1 is a side elevation of a machine 40 constructed in accordance with this invention.

Figure 2 is a detailed section on the line 2—2 of Figure 1, the pressing and positioning means being thrown back and the view 45 being on a reduced scale.

Figure 3 is a section similar to Figure 2 but taken on an enlarged scale and showing the positioning means brought forward.

In the construction of this invention there 50 is provided a base 10 and extending upward from this base are bearing standards 11 and 12 wherein is revolvably mounted a shaft 13. This shaft 13 is driven by a clutch mechanism indicated in general at 14 and which is 55 preferably the type of clutch mechanism il-

lustrated and described in my copending application filed the 27th day of April, 1921, and bearing the Serial Number 464,831. The control lever for this clutch mechanism is shown at 15.

The shaft 13 extends through the bearing member 11 and carries on its outer end a hollow cylinder 16 provided at one side with a series of radial openings 17 having their axes in the same plane.

Extending up from the base 10 is a third bearing standard 18 provided on its upper end with a sleeve 19 wherein is slidably and rotatably mounted a pipe 20 closed in the end 21 and carrying at its other end a head 22 facing the cylinder 16. The side of the head adjacent the cylinder is recessed to receive a rubber or other elastic 23, the pipe 20 extending entirely throughout the head and back as clearly shown in Figure 1. Connected to the sleeve 19 is a section pipe 24 and surrounding the pipe 20 is a channel 25 which communicates with the interior of said pipe 20 by ports 26. When the head 22 is in contact with the cylinder 16 the pipe 24 communicates with the channel 25 so that the pipe 20 forms an extension of the suction pipe. Extending upward from the base 10 is a bracket 27 to which is pivoted one end of the hand lever 28. This hand lever 28 is connected to a link 29 from which an arm 30 extends downwardly and is provided on its lower end with a shipper fork 31 engaging a grooved shipper collar 32 forming part of the head 22. Member 11 is extended upward 90 of the bearing, and is provided on its upper end with a laterally extending arm 33 to which is pivoted the upper end of a shipper lever 34 engaging a channel 35 formed in an ejector head 36 mounted to slide longitudinally over the cylinder 16. Projecting from the lever 34 is a pin 37 which is received within a slot 38 formed in the link 29. Projecting from the member 11 is an arm 39 provided with limit stop pins 40 between which 95 the shipper lever 34 may swing.

Extending upward from the base 10 is a bracket 41 to which is pivoted the angle of a bell crank lever 42. One arm of this lever extends outward towards the front of the 105 base 10 and is provided with a treadle 43. The other arm of this lever extends upward behind the cylinder 16 and is provided on its upper end with a presser plate 44 which, when the treadle 43 is pushed fully down, 110

bears against the upper part of the cylinder 16. Secured to the central portion of the presser plate and projecting through a suitable opening therein is a spring positioning finger 45. In order to normally hold the plate 44 and finger 45 away from the cylinder ends there is provided on the lever arm 42 a loop hole eye to which is connected the upper end of a tension spring 47 having its lower end connected to an eye 48 extending upward from the base 10. In the operation of the device it is to be understood that a number of strips of paper or the like material are provided, each of the strips being cut to the proper width and length and each having one end glued. The operator takes one of these strips and places it on the cylinder, the lever 28 having been moved to the right so as to produce a partial vacuum inset cylinder. At the time of positioning the paper strip S the treadle 43 is depressed until the finger 45 engages the cylinder 16. Thus the strip S will lie over the openings 17 and will be held firmly in position by the action of the partial vacuum in the cylinder 16. The operator may then let go of this strip. The operator now grasps the lever 15 with her right hand and throws it forward so that the cylinder 16 is caused to revolve by the action of the clutch 14; the shaft 13 and cylinder 16 will now revolve. Under these conditions the strip S will force the spring finger 45 upward and the strip will be caused to go around with the cylinder, the latter being provided with corrugations 49 the better to hold the strip while revolving as well as to lessen the friction between the completed can body and cylinder during the process of removing the said cylinder. When the required extent of revolution has been almost completed the operator moves the lever 15 backward. This, as described in my copending application above referred to, brings the shaft to a stop. Further depression of the treadle will then force the plate 44 firmly down on the strip S, the ends of the strip at this time overlapping so that the glue or other adhesive will cause said ends to firmly stick together. Next, the operator grasps the lever 28 with her left hand and moves the same to the left. The first form of this movement of the lever 28 is to draw the head 22 away from the cylinder 1 to close off the ports 26. This breaks the vacuum in the cylinder 16. Further movement of the lever 28 brings the right hand end of the slot 38 into engagement with the pin 37 and causes movement of the lever 34 to the left. This moves the head 36 to the left and consequently the formed can body is pushed off of the cylinder 16. It must be noted that at this time the operator has removed her foot from the treadle 23 so that the plate 44 and finger 45 assume the position shown in Figure 2 and are thus

entirely out of the way of the movement of head 36.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. In a device of the kind described, a body former consisting of a hollow rotatable cylinder closed at one end and provided with a series of lateral apertures, means for rotating the cylinder, a plate adapted to close the open end of the cylinder and movable into and out of contact therewith, and a suction pipe connected to the plate and affording communication with the interior of the cylinder.

2. In a device of the kind described, a body former consisting of a hollow rotatable cylinder closed at one end and provided with a series of lateral apertures, means for rotating the cylinder, a plate adapted to close the open end of the cylinder and movable into and out of contact therewith, a suction pipe connected to the plate and affording communication with the interior of the cylinder, an ejector mechanism associated with said cylinder, and means to move the plate away from the cylinder and operate the ejector mechanism successively.

3. In a device of the kind described, a body former consisting of a hollow rotatable cylinder having one end closed and provided with lateral suction openings, a closure for the other end of the cylinder, a suction pipe carrying said closure, and having the end remote from the closure closed, said pipe having lateral ports adjacent the closed end, a bearing wherein said pipe is slidably and rotatably mounted, and having a vacuum chamber therein, the lateral ports of the pipe communicating with the vacuum chamber when the closure is against the cylinder, a main suction pipe in constant communication with the vacuum chamber, and means to move the closure to and from the cylinder and the ports into and out of registry with the vacuum chamber.

4. In a device of the kind described, a body former consisting of a hollow rotatable cylinder having one end closed and provided with lateral suction openings, a closure for the other end of the cylinder, a suction pipe carrying said closure and having the end remote from the closure closed, said pipe having lateral ports adjacent the closed end, a bearing wherein said pipe is slidably and

- rotatably mounted and having a vacuum chamber therein, the lateral ports of the pipe communicating with the vacuum chamber when the closure is against the cylinder, 5
 5 a main suction pipe in constant communication with the vacuum chamber, an ejector mechanism slideable along said cylinder, and means for moving the closure and pipe to break the vacuum in the cylinder and bring 10
 10 the ports out of registry with the vacuum chamber and thereafter actuating the ejector mechanism.
5. In a device of the kind described, a body former consisting of a hollow rotatable cylinder having one end closed and provided with lateral suction openings, a closure for the other end of the cylinder, a suction pipe carrying said closure and having the end remote from the closure closed, said pipe 15
 20 having lateral ports adjacent the closed end, a bearing wherein said pipe is slidably and rotatably mounted and having a vacuum chamber therein, the lateral ports of the pipe communicating with the vacuum chamber 25
 25 when the closure is against the cylinder, a main suction pipe in constant communication with the vacuum chamber, an ejector collar slideable along said cylinder, a shipper lever pivoted at one end and operatively connected to the collar, a hand lever, a link connected 30
 30 to the collar, a hand lever, a link connected to the hand lever and having a lost motion connection with the shipper lever pivoted at one end and operatively connected to the collar, a hand lever, a link connected 35
 35 to the hand lever and having a lost motion connection with the shipper lever, and a shipper arm carried by the link and having operative connection with the closure.
6. In a device of the kind described, a body former consisting of a hollow rotatable cylinder closed at one end and provided with a series of lateral apertures, means for rotating the cylinder, a plate adapted to close the open end of the cylinder and movable 40
 45 into and out of contact therewith, a suction pipe connected to the plate and affording communication with the interior of the cylinder, and stop means adapted to ensure position of a paper blank over the lateral 50
 50 openings in the cylinder.
7. In a device of the kind described, a body former consisting of a hollow rotatable cylinder closed at one end and provided with a series of lateral apertures, means for rotat- 55

- ing the cylinder, a plate adapted to close the open end of the cylinder and movable into and out of contact therewith, a suction pipe connected to the plate and affording communication with the interior of the cylinder, an ejector mechanism associated with said cylinder, means to move the plate away from the cylinder and operate the ejector mechanism successively, stop means adapted to ensure position of a paper blank over the lateral openings in the cylinder, and a presser plate carrying said stop means and movable toward and from the cylinder.
9. In a device of the kind described, a body former consisting of a hollow rotatable cylinder closed at one end and provided with a series of lateral apertures, means for rotating the cylinder, a plate adapted to close the open end of the cylinder and movable into and out of contact therewith, a suction pipe connected to the plate and affording communication with the interior of the cylinder, stop means adapted to ensure position of a paper blank over the lateral openings in the cylinder, and a presser plate carrying said stop means and movable toward and from the cylinder.
10. In a device of the kind described, a body former consisting of a hollow rotatable cylinder closed at one end and provided with a series of lateral apertures, means for rotating the cylinder, a plate adapted to close the open end of the cylinder and movable into and out of contact therewith, a suction pipe connected to the plate and affording communication with the interior of the cylinder, an ejector mechanism associated with said cylinder, means to move the plate away from the cylinder and operate the ejector mechanism successively, stop means adapted to ensure position of a paper blank over the lateral openings in the cylinder, and a presser plate carrying said stop means and movable toward and from the cylinder.

In testimony whereof I affix my signature.
 FREDERICK COATES.
